BOBBIN STRIPPER

Edgar Allen Terrell, Charlotte, N. C., assignor to
The Terrell Machine Company, Charlotte,
N. C., a corporation

Application November 24, 1934, Serial No. 754,667

8 Claims. (Cl. 28—19)

The invention has relation to machines of the class used in the textile industry for the purpose of stripping so-called feeler-waste, i. e., residues of weft or filling, from bobbins that have been 5 expelled from the working shuttle of an automatic weft-replenishing loom in bobbin-changing operations brought about under the control of a so-called weft or filling feeler. More particularly, it relates to bobbin-stripping machines of 10 the type having blades or the like by which the bunch of weft or filling remaining on an expelled bobbin is removed from the bobbin-barrel by a scraping action taking place lengthwise along the bobbin-barrel.

15 For an example of the type of bobbin-stripper to which my present invention is applicable, I refer to my former Patent No. 1,740,127, dated December 17, 1929, in which is used a puller-block carrying a pair of gripping jaws adapted to grip 20 the head of the bobbin to draw or pull the same through the stripper-blades to remove the residue of weft or filling. The special object of the present invention is to provide this type of machine with an air-blast attachment which, without interfering with or delaying the usual stripping operation, will automatically blow out any 25 lint that may have accumulated in the bore of the bobbin to thereby clear the interior of the bobbin of lint particles that might interfere with its proper seating on the spindle, as more fully hereinafter set forth.

In the drawing annexed,

Fig. 1 is a side elevation of a preferred form of my apparatus, so much of the adjacent parts of 35 the usual bobbin-stripper machine being shown as is desirable in properly illustrating my present invention;

Fig. 2 is a longitudinal sectional view of the nozzle devices;

40 Fig. 3 is a detail view partly in section of a bracket for actuating a valve rod; and

Fig. 4 is a detail plan view of the puller-head or block.

45 Referring to the drawing by reference characters, 5 designates an air-cylinder mounted on the usual frame of the bobbin-stripper in horizontal alinement with the bobbin supports in the machine and positioned close to the point where the tip of the bobbin will lie when it is positioned 50 in the machine ready for stripping, said cylinder being provided with a lip extension 6 adapted to receive and support the tip end of the bobbin 7 when it is in position for stripping. When thus placed, the bobbin will lie in position to be grasped 55 by the usual jaws 8 carried by the usual puller 9,

which is adapted to be reciprocated on the bed of the machine by mechanism not shown. An abutment 10 is screwed into the face of the puller in position to receive the thrust of the head of the bobbin when it is moved a slight distance toward 5 the puller-head by the air-blast, hereinafter described. The forward end of this abutment is T-shaped so that when the bobbin is forced against it, it will not plug the bore of the bobbin but will leave it sufficiently open to permit free 10 passage of the cleaning blast of air. The abutment 10 is desirably in the form of a screw tapped into the face of the bore so that it may be adjusted toward and from the usual bobbin supports in the machine; and in order that the 15 adjustments of this abutment may be maintained, I provide a set screw 11 tapped up through a hole in the puller-head. Clamped to the underside of the puller-head is an angle bracket 12, its depending end being provided with a valve tappet 13 20 which is desirably in the form of a screw tapped into the bracket to enable the tappet to be adjusted toward and from the adjacent end of a valve-rod 14. This valve-rod is mounted slidingly in a sleeve 15 affixed to a bracket 16 which is mounted on the machine frame, preferably by means of a U-bolt 17. The other end of the valve-rod extends beyond the end of the sleeve 15 25 and is provided with a cotter-pin 18 to prevent the valve-rod sliding out of the sleeve. Adjacent 30 to this end of the valve-rod 14 is arranged a valve stem 19 which projects from the casing of a valve 20 of the usual valve-disk type, this valve being inserted in an inlet-pipe 21, which inlet pipe and valve are rigidly affixed to the bracket 16 by means 35 of U-bolts 22.

Attached to the outlet end of the inlet-pipe 21 40 is a piece of flexible tubing 23, and the outlet end of this flexible tubing is affixed to the inlet end of the nozzle-pipe 24, which nozzle-pipe is supported rigidly on bracket 16. The outlet end of this pipe 24 delivers air to the interior of the aforesaid air-cylinder at its rear end, and in order that this pipe 24 and the air-cylinder 5 may be longitudinally 45 adjusted with reference to the puller-head to accommodate bobbins of different lengths, I provide for adjusting the pipe 24 in the bracket by means of a set-screw 25. Within the air-cylinder 5, I mount a long, slideable piston-like nozzle 26, which desirably has a nice fit, but not necessarily an air-tight fit, in the interior of the cylinder. This piston-nozzle is provided with a central bore 26' extending throughout its length 50 having a cross-sectional area less than the area of the pressure-end of the piston. This piston is 55

5 moved toward the bobbin 7 by means of the air-blast and after the air-blast has completed its work the piston is returned to its normal position against seat 21 by means of a retractile spring 28 connecting two pins 29 and 30, the former of which is mounted on the cylinder at the rear end thereof and the other of which is tapped into the wall of the piston through a slot 31 formed in the bottom-side of the cylinder. The forward end of 10 the piston is desirably cupped to thereby provide a beveled or rounded seat 32 for proper engagement with the tip of the bobbin when the piston is projected forwardly by the air-blast, when the blast is turned on to clean the bore of the bobbin.

15 The parts may be so adjusted that when the puller-head has been advanced to a point where it is about to grasp the head of the bobbin, the tappet 13 will strike the valve-rod 14 and thus open the valve 20. Thereupon a blast of air, from 20 a source not shown, will enter the rear end of the cylinder 5 and quickly force the piston 26 forwardly into engagement with the tip of the bobbin, and then the air-blast will have a clear path 25 through the bore of the bobbin to clean the lint therefrom. As heretofore stated, the pressure area of the piston at its rear end is greater than the area of the nozzle-passage 26 so that notwithstanding the fact that the air has clear passage 30 through the piston, the piston will be quickly advanced into contact with the tip of the bobbin. As the grippers pull the bobbin away from the nozzle, the nozzle will follow the bobbin until stop-pin 30 reaches the forward end of the slot 31, whereupon the piston will stop and the air 35 will be exhausted out through the bore in the piston. Then when the air-pressure is thus removed, the spring 28 will quickly return the piston to its position against seat 21, ready for the next operation.

40 In accordance with the provisions of the patent statutes, I have herein described the principle of operation of my invention, together with the apparatus which I now consider to represent the best embodiments thereof, but I desire to have it 45 understood that the apparatus disclosed is only illustrative and that the invention can be carried out by other means.

I claim:

1. In combination with a bobbin-stripping machine, having devices for externally stripping a bobbin while in stripping position, an apparatus for subjecting the bore of the bobbin to an air-blast while the bobbin is in stripping position, embodying an air-cylinder, a nozzle slidably mounted therein adapted to be moved into contact with the tip of the bobbin during a stripping operation, said nozzle having an air-passage, and timed means for delivering a blast of air into said cylinder against the pressure head of the nozzle to thus move the nozzle into engagement with the tip of the bobbin and subject the interior of the bobbin to the same blast of air.
2. The structure recited in claim 1, said air-passage extending throughout its length of the nozzle.
3. The structure recited in claim 1, the cross-sectional area of said air-passage through the

bobbin being less than the pressure-area of the pressure-end of the nozzle to thereby insure the advance of the nozzle into operative position and at the same time permit the same blast of air to pass through the air-passage of the nozzle.

4. The structure recited in claim 1, said apparatus embodying a valve-tappet mounted on a movable part of the bobbin-stripping machine, a valve-rod adapted to be actuated by said tappet, an inlet-pipe carrying a stationary valve adapted 10 to be operated by said valve-rod, and conduit means connecting the outlet end of said inlet-pipe with the inlet end of the cylinder.

5. The structure recited in claim 1, said apparatus embodying an inlet-pipe provided with a 15 valve, a flexible conduit connection between the outlet-end of said inlet-pipe and one end of a pipe connected at its other end to the inlet-end of the cylinder, and means for adjustably supporting this latter pipe, and timed devices for actuating 20 said valve.

6. In combination with a bobbin-stripping machine, an apparatus for subjecting the bore of the bobbin to an air-blast while the bobbin is in stripping position, embodying a stationary air-cylinder, a nozzle slidably mounted therein adapted to be moved into contact with the tip of the bobbin during a stripping operation, and means actuated from a part of the bobbin-stripping machine for delivering a blast of air into said cylinder to thus 30 move the nozzle into engagement with the tip of the bobbin and by the same blast of air subject the bore to a cleaning action.

7. In combination with a bobbin-stripping machine, an apparatus for subjecting the bore of the 35 bobbin to an air-blast when the bobbin is in stripping position, embodying a nozzle adapted to engage the tip of the bobbin while in stripping position to discharge an air-blast into the bore of the bobbin, and air-blast means for moving said 40 nozzle into operative position and holding it there while the same blast of air enters the bore of the bobbin to subject the same to a cleaning action.

8. In combination with a bobbin-stripping machine of the puller-head type having devices for 45 externally stripping a bobbin while in stripping position, an apparatus for subjecting the bore of the bobbin to an air-blast while the bobbin is in stripping position, embodying a stationary air-cylinder, a nozzle slidably mounted therein 50 adapted to be moved into contact with the tip of the bobbin during a stripping operation, said nozzle having an air-passage and timed means for delivering a blast of air into said cylinder against the pressure head of the nozzle to thus 55 move the nozzle into engagement with the tip of the bobbin and subject the interior of the bobbin to the same blast of air, said apparatus embodying also a valve-tappet mounted on the puller-head of the bobbin-stripping machine, a valve-rod adapted to be actuated by said tappet when the puller-head is in position to grasp the bobbin, a stationary valve adapted to be operated by said valve-rod, and conduit means connecting said valve with the inlet-end of said cylinder.

EDGAR ALLEN TERRELL.
